CLAIM

The ornamental design for a pendant with two stone setting, as shown and described.

DESCRIPTION

FIG. 1 is a front perspective view of a pendant with two stone setting according to the present invention;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The broken lines shown in the figures illustrate unclaimed portions of the design.
